UNITED STATES PATENT OFFICE.

GEORGE E. TAYLOR, OF ROCHESTER, NEW YORK, ASSIGNOR TO TAYLOR BROTHERS COMPANY, OF ROCHESTER, NEW YORK, A CORPORATION OF NEW YORK.

DESIGN FOR A THERMOMETER-MOUNTING.

SPECIFICATION forming part of Design No. 35,282, dated November 12, 1901.

Application filed September 16, 1901. Serial No. 75,616. Term of patent 7 years.

To all whom it may concern:

Be it known that I, GEORGE E. TAYLOR, a citizen of the United States, residing at Rochester, in the county of Monroe and State of New York, have invented and produced a new and original Design for a Thermometer-Mounting, of which the following is a full, clear, and exact specification, in connection with the accompanying drawing, forming a part thereof.

The drawing illustrates a front elevation of a thermometer-mounting constructed according to my design.

The design embodies a base 1, having an irregular outline and resembling, generally,

a tobacco-leaf, and having upon its surface the central vein or rib 2, in line with which is a slot 3, and at either side of the latter are usual degree-indications, as shown. Extending over the face of the mounting are a series ^{2c} 4, representing the smaller veins of the leaf.

I claim—

The design for a thermometer-mounting, substantially as shown and described.

GEORGE E. TAYLOR.
